(57) **CLAIM**

The ornamental design for a garment, as shown and described.

DESCRIPTION

FIG. 1 is a front view of a garment according to the design; FIG. 2 is a rear view thereof; FIG. 3 is a right side view thereof; FIG. 4 is a left side view thereof; FIG. 5 is a front perspective view thereof; FIG. 6 is a rear perspective view thereof; FIG. 7 is a front view thereof shown in an environment of use; and, FIG. 8 is a rear view thereof shown in an environment of use. The portions of the garment shown in broken lines in FIGS. 1-8 form no part of the claimed design. The broken line showing of the arms, torso, neck, and head in FIGS. 7-8 is for the purpose of illustrating portions of the environmental structure and forms no part of the claimed design.

1 Claim, 8 Drawing Sheets
